S. D. GREEN.
AIR SUPPLY CONTROL DEVICE.
FILED NOV. 16, 1921.

UNITED STATES PATENT OFFICE.

STEPHEN D. GREEN, OF GILMAN, IOWA.

AIR-SUPPLY-CONTROL DEVICE.

Application filed November 16, 1921. Serial No. 515,658.

To all whom it may concern:

Be it known that I, STEPHEN D. GREEN, a citizen of the United States, and a resident of Gilman, in the county of Marshall and State of Iowa, have invented a certain new and useful Air-Supply-Control Device, of which the following is a specification.

The object of my invention is to provide an air supply device of simple, durable and inexpensive construction for crank cases and carburetors for internal combustion engines.

More particularly, it is my object to provide a mechanism combined with an internal combustion engine, whereby air may be taken, from the crank case and supplied to the carburetor, which mechanism includes an adjustable control device for varying the amount of air taken from the crank case.

With these and other objects in view, my invention consists in the construction, arrangement and combination of the various parts of my device, whereby the objects contemplated are attained, as hereinafter more fully set forth, pointed out in my claim, and illustrated in the accompanying drawings, in which:

Figure 1 shows a side elevation of an engine equipped with a device embodying my invention, the foot board and dash of the car on which the engine is installed being shown in vertical section.

Figure 2 shows a top or plan view of the engine and device; and

Figure 3 shows a perspective view of a part of the device and control mechanism therefor.

In the accompanying drawings, I have used the reference numeral 10 to indicate generally the dash of a motor vehicle, having the foot board 11. Located forwardly with relation to the dash and foot board is an engine 12, having the crank case 13, back of which is the fly wheel case 14 and the transmission case 15.

On one side of the engine is the intake manifold 16 which communicates with the carburetor 17.

In front of the crank case 13 is the upwardly extending so-called breather pipe 18. Communicating with the pipe member 19 between its ends is a pipe 21, extended rearwardly and curved as at 21 to connect with the air intake opening of the carburetor 17.

An air supply device 22 communicates with the transmission case 15 and extends

upwardly therefrom. The pipe 22 has at its upper end a funnel 23 on which is mounted a strainer 24 held in place by a resilient band 25. The strainer 24 may be of cloth or any suitable material or structure for the purpose.

The upper end of the pipe 19 has a partial closure member 26 and an open portion 27. A rotary damper member 28 is pivotally mounted on the closure member 26 by means of a screw bolt or the like 29. On the damper 28 is an upwardly extending ear 30 to which is pivoted a rod 31, extending upwardly and rearwardly through the dash 16 and having a head 32 on its upper end.

It will be seen that when the engine is running and the damper 28 is closed, the air supply from the carburetor will be drawn through the crank case.

This has a number of advantages in the operation of an engine whether on a tractor or pleasure car. I have employed the device on my own tractor and pleasure car, and find that by drawing the air for the carburetor through the crank case, the air is furnished to the carburetor at a much more nearly uniform temperature than is usually possible. The supply of air at approximately uniform temperature, makes it possible to more accurately control the fuel supply and results in a substantial saving of fuel.

Where gasoline or the lower grade of hydro-carbon oils are employed, oil may be put into the crank case through the pipe 22, after the removal of the band 25 and the strainer 24, or through the opening 27, so that my device does not interfere with the supplying of oil to the crank case.

It will be noted that the intake pipe 22 is located at one end of the crank case and the pipe 19 at the outer end, so that the air must pass entirely through the crank case before being carried to the carburetor. This, I consider, one of the most important features of my invention. While the intake and outlet pipes 22 and 19 may be located at either end of the engine, they should be located at opposite ends. I preferably locate the pipe 19, so that it may be mounted on the breather pipe for convenience and cheapness of installation, and also because the pipe 20 then extends along the heated engine for preventing the air from being cooled during its passage from the crank case to the carburetor.

It is also desirable to take the air from the crank case for the reason that with a device of the kind herein shown, any exhaust gases may have escaped past the piston 5 and gone into the crank case to be drawn out through the pipes 19 and 20 and will not remain in the crank case. I find that I am thus able to keep my oil considerably cleaner than would otherwise be possible.

Another advantage of the construction here shown, wherein the air is drawn the entire length of the crank case, arises from the fact that the cool air helps to cool the lower part of the engine and assists in preventing overheating of the bearings.

My device is of very simple and inexpensive construction and can be readily and easily made and installed on a car or tractor.

I have shown the device in my drawings for purposes of illustration, as mounted on an ordinary Ford engine, but it will be seen that the device may be readily adapted for installation on a great variety of makes of engines.

Considerable control of the air flow through the crank case is afforded by means of a damper 28 and the operating mechanism therefor. By varying the size of the opening 27, more or less air can be drawn through the crank case, and less or more

air will be taken from the atmosphere directly.

Some changes may be made in the construction and arrangement of the various parts of my device, without departing from the essential features and purposes of my invention, and it is my intention to cover by my claim, any modified forms of structure, or use of mechanical equivalents, which may be reasonably included within their scope.

I claim as my invention:

In combination with a motor vehicle 45 having a floor board, a dash, and an engine provided with a crank case and a carburetor, a pipe communicating with the breather of the crank case, a second pipe communicating with said first pipe and communicating 50 with the air intake tube of the carburetor, a breather pipe extending from the crank case to a considerable distance thereabove and through the floor boards, a screen enclosing the upper end of said breather pipe, 55 the upper end of the first pipe having a rotatable valve for regulating the size of opening therein, and a rod connected with said valve and extending through the dash, where it may be manipulated for controlling 60 the valve.

Des Moines, Iowa, November 4, 1921.

STEPHEN D. GREEN.,
